WIND PROPELLED OUTBOARD MOTOR

Benjamin B. Dorr, West Toledo, Ohio

Application June 3, 1940, Serial No. 338,603

5 Claims. (Cl. 115—3)

This invention relates to a wind-propelled outboard motor and has for an object to provide a device of this character in which the shaft for the water propeller is detachably clutched to the wind-driven main shaft and the main shaft housing and the propeller shaft housing are hingeably connected together at the clutch of the shafts so that the propeller and rudder may rock upwardly upon hitting an object in the water and prevent breakage and fouling of the water propeller and rudder.

A further object is to provide a device of this character in which a single spring performs the dual function of returning the water propeller and rudder to operative position each time these parts are displaced upwardly and at the same time tends to keep the boat on a straight course without the operator holding onto the tiller handle.

A further object is to provide a device of this character which may be easily attached to and removed from a boat for use in connection with outboard motors without alterations to the boat.

A further object is to provide apparatus of this character which will be formed of a few strong, simple and durable parts, which will be inexpensive to manufacture, and which will not easily get out of order.

With the above and other objects in view the invention consists of certain novel details of construction and combinations of parts herein-after fully described and claimed, it being understood that various modifications may be resorted to within the scope of the appended claims without departing from the spirit or sacrificing any of the advantages of the invention.

In the accompanying drawings forming a part of this specification:

Figure 1 is a plan view of a wind propelled outboard motor constructed in accordance with the invention and shown applied to the stern portion of a boat.

Figure 2 is a longitudinal section view, with parts in elevation, of the outboard motor.

Figure 3 is a detail side elevation showing the water propeller and rudder rocked upwardly to released position.

Figure 4 is a cross sectional view taken on the line 4—4 of Figure 2 showing the rope brake and tiller handle.

Figure 5 is a detail cross sectional view taken on the line 5—5 of Figure 4.

Figure 6 is a detail cross sectional view taken on the line 6—6 of Figure 2.

Figure 7 is a detail cross sectional view taken on the line 7—7 of Figure 2.

Referring now to the drawings in which like characters of reference designate similar parts in the various views, 10 designates a main shaft which is received axially in a main shaft housing 11, the upper end of which is provided with an

extension 12 revolvably secured to the housing by a sectional flanged coupling 13, best shown in Figure 7, which receives flanges formed on the extension and on the housing and between which flanges ball bearings 14 are disposed.

The revolvable extension is provided with a hollow head 15 through the bottom of which the main shaft 10 projects. A wind wheel 16 is mounted on one end of a stub shaft 17 which is journaled in the wall of the head. Meshing beveled gears 18 and 19 connect the stub shaft with the main shaft.

A wind vane 20 is provided with superposed ears 21 through which, and superposed ears 22 on the hollow head 15, a bolt 23 is passed. A helical spring 24 is sleeved on the bolt above the upper ear 21 of the vane to hold projections 25 on the ears 21, seated selectively in sockets 26 in the hollow head ears so that the vane may be turned into operative or released position to respectively hold the wind wheel into or out of the wind.

A propeller shaft housing 27 is disposed below and in alinement with the main shaft housing 11. The upper end of the propeller shaft housing is provided with the lower half section 28 of a brake housing 29, the upper half section of the brake housing being carried by the main shaft housing 11 and secured to the lower half section by screw bolts 31, or other connectors.

A hollow tiller handle 32 is secured to the brake housing 29 and when the tiller handle is manually swung to the right or to the left the shaft housing 27 will be correspondingly turned to swing a rudder 33 which is fixed to the lower end of the shaft housing 27 by set screws 34, or other connectors.

A bearing sleeve 35 is loosely mounted on the housing 27 below the brake housing 29 and is adjustably secured vertically on the housing 27 by split ring collars 36 disposed above and below the sleeve, which latter is also a split ring collar.

A securing arm 37 projects forwardly from the sleeve 35 and is telescopically received in a hollow arm 38 having an inverted U-shaped clamp 39 on the end adapted to be placed astride the stern portion 40 of a boat 41 and be secured thereto by set screws 42. Set screws 43 adjustably secure the arm 37 in the hollow arm 38. The sleeve 35 is provided near the bottom with ears 44, as best shown in Figure 6. Securing rods 45 are bolted to the ears as shown at 46 and are telescopically received in hollow arms 47 which terminate in balls 48 that are received in sockets 49 carried by angular brackets 50 which are placed astride the rear outer corners of the stern 40 of the boat and are secured thereto by cables 51 which are trained forwardly along the sides of the bolts and are secured to rings 52 or other convenient parts of the boat to detachably mount the device on the boat.

The propeller shaft housing 27 is formed in two sections, an upper section 53 and a lower section 54 connected together by a break joint including hinge ears 55 and 56 carried by the sections and a hinge pin 57 passed through the ears. The ears are formed on the rear sides of the sections and permit the lower section of the housing to tilt upwardly when the rudder 33 is struck by an article in the water and permit the rudder to ride safely over the obstruction without damage. For holding the sections normally aligned a nipple 58 is formed on the upper section 53 and enters the upper end of the lower section 54 which latter is provided with a stop wall 59 against which the nipple abuts.

A propeller shaft 60 is journaled in the stop wall 59 and in a lower stop wall 61 disposed in the lower section 54 of the propeller shaft housing. The lower end of the propeller shaft is equipped with a bevel gear 62 which meshes with a bevel gear 63 which is secured to the inner end of a stub shaft 64 which is mounted in a tubular bearing 65 and to which is secured a propeller 66. At the break joint between the upper and lower sections of the propeller shaft housing 27 the main shaft 10 is clutched to the propeller shaft 60 through the medium of upper and lower clutch members 67 and 68 which are carried respectively by the lower end of the main shaft 10 and the upper end of the propeller shaft 60. When the joint breaks to permit the rudder and propeller to rock upwardly and rearwardly the clutch members will be de-clutched and when the parts return to normal operative position the clutch members will be clutched to connect the main shaft to the propeller shaft to drive the latter.

A helical spring 69 is secured at the lower end to an eye rod 70 which extends forwardly from the lower section 54 of the propeller shaft housing 27. The upper end of the spring is secured in an eye 71 carried by the tubular arm 38 of the securing arm 37. The spring passes between the hollow arms 47 and normally holds the rudder 33 in position to guide the boat on a straight course without attention from the operator. The spring also returns the lower section 54 of the propeller shaft housing 27 to operative vertical position each time it is displaced upwardly by the rudder 33 striking an object in the water.

As best shown in Figure 1, a transverse brace rod 72 is secured at one end to the end of one of the downwardly inclined telescopedically assembled securing rods 47 and is telescopedically received in the hollow end 73 of a brace rod 74 which is secured to the other downwardly extending securing rod 47. A set screw 75 adjustably secures the brace rods 72 and 74 together.

The brake comprises a pulley 76 which is fixed to the main shaft 10 inside of the brake housing 29. A rope 77 is trained around the pulley and is directed through the hollow tiller arm 32, as best shown in Figure 4, the ends of the rope being connected together at the free end of the tiller arm by a ring 78. The ring may be manually pulled outwardly to tighten the rope on the pulley 76 and slow down and eventually stop rotation of the main shaft 10 whenever this becomes necessary.

Since the operation of the parts has been described as the description of the parts progressed, it is thought the invention will be fully understood without further explanation.

What is claimed is:

1. In a wind propelled outboard motor, propeller and steering mechanism, a wind wheel connected with the propeller mechanism, a hinged joint between the steering mechanism and the propeller adapted to disconnect the propeller from the wind wheel in the event of the propeller striking an obstruction, and a spring connected to the steering mechanism for normally holding the propeller connected to the wind wheel.
- 5 2. In an outboard motor, upper and lower aligned tubular housings, means for securing the upper housing to a boat, a main driving shaft in the upper housing, a driven propeller shaft in the lower housing, a propeller connected to the propeller shaft and carried by the lower housing, a hinge joint connecting the housings at their opposed ends, clutch means detachably connecting the shafts at said joint, and yielding means holding the lower housing aligned with the upper housing and permitting the lower housing and propeller shaft to rock upwardly at said joint upon contact of the propeller with an object in the water.
- 10 3. In an outboard motor upper and lower aligned tubular housings, means for securing the upper housing to a boat, a hollow tiller handle connected to the upper housing for turning the housing axially, a driven propeller shaft in the lower shaft, a propeller connected to the propeller shaft and carried by the lower housing, a rudder carried by the lower housing a hinged joint connecting the housings at their opposed ends, clutch members detachably connecting the shafts at said joint, and yielding means holding the lower housing aligned with the upper housing and permitting the rudder, lower housing and propeller shaft to rock upwardly at said joint upon contact of the propeller or rudder with an object in the water.
- 15 4. In a wind propelled outboard motor, comprising an upper and lower aligned tubular housing pivoted together, means for securing the upper housing to a boat, a main drive shaft in the upper housing, wind operated means for driving the main shaft, a propeller shaft in the lower housing, clutch members carried by the ends of the main shaft and propeller shaft for connecting the same together, a spring connected to the lower tubular housing and to the upper housing, a drum carried by the main driving shaft, and a brake band passing around the brake drum for retarding the movement of the main driving shaft.
- 20 5. In a wind propelled outboard motor, comprising upper and lower tubular housings hinged together, an adjustable means for securing the upper housing to a boat, a main drive shaft in the upper housing, wind propelled means for driving the main shaft, a propeller shaft in the lower housing, a propeller carried by the lower housing and driven by a gearing from the propeller shaft, clutch means carried by the main shaft and the propeller shaft connecting the shafts together when the housings are in aligned position, a coil spring connected to the lower housing and having its opposite end connected to the housing securing means, a drum carried by the main driving shaft, and a cable passing around said drum and having its ends secured to a hand operated means, whereby the cable may be tightened around the drum for retarding the movement of the main drive shaft.
- 25 6. In a wind propelled outboard motor, comprising upper and lower aligned tubular housings hinged together, means for securing the upper housing to a boat, a main driving shaft in the upper housing, wind propelled means for driving the main shaft, a propeller shaft in the lower housing, a propeller carried by the lower housing and driven by a gearing from the propeller shaft, clutch means carried by the main shaft and the propeller shaft connecting the shafts together when the housings are in aligned position, a coil spring connected to the lower housing and having its opposite end connected to the housing securing means, a drum carried by the main driving shaft, and a cable passing around said drum and having its ends secured to a hand operated means, whereby the cable may be tightened around the drum for retarding the movement of the main drive shaft.
- 30 7. In a wind propelled outboard motor, comprising upper and lower aligned tubular housings hinged together, means for securing the upper housing to a boat, a main driving shaft in the upper housing, wind propelled means for driving the main shaft, a propeller shaft in the lower housing, a propeller carried by the lower housing and driven by a gearing from the propeller shaft, clutch means carried by the main shaft and the propeller shaft connecting the shafts together when the housings are in aligned position, a coil spring connected to the lower housing and having its opposite end connected to the housing securing means, a drum carried by the main driving shaft, and a cable passing around said drum and having its ends secured to a hand operated means, whereby the cable may be tightened around the drum for retarding the movement of the main drive shaft.
- 35 8. In a wind propelled outboard motor, comprising upper and lower aligned tubular housings hinged together, means for securing the upper housing to a boat, a main driving shaft in the upper housing, wind propelled means for driving the main shaft, a propeller shaft in the lower housing, a propeller carried by the lower housing and driven by a gearing from the propeller shaft, clutch means carried by the main shaft and the propeller shaft connecting the shafts together when the housings are in aligned position, a coil spring connected to the lower housing and having its opposite end connected to the housing securing means, a drum carried by the main driving shaft, and a cable passing around said drum and having its ends secured to a hand operated means, whereby the cable may be tightened around the drum for retarding the movement of the main drive shaft.
- 40 9. In a wind propelled outboard motor, comprising upper and lower aligned tubular housings hinged together, means for securing the upper housing to a boat, a main driving shaft in the upper housing, wind propelled means for driving the main shaft, a propeller shaft in the lower housing, a propeller carried by the lower housing and driven by a gearing from the propeller shaft, clutch means carried by the main shaft and the propeller shaft connecting the shafts together when the housings are in aligned position, a coil spring connected to the lower housing and having its opposite end connected to the housing securing means, a drum carried by the main driving shaft, and a cable passing around said drum and having its ends secured to a hand operated means, whereby the cable may be tightened around the drum for retarding the movement of the main drive shaft.
- 45 10. In a wind propelled outboard motor, comprising upper and lower aligned tubular housings hinged together, means for securing the upper housing to a boat, a main driving shaft in the upper housing, wind propelled means for driving the main shaft, a propeller shaft in the lower housing, a propeller carried by the lower housing and driven by a gearing from the propeller shaft, clutch means carried by the main shaft and the propeller shaft connecting the shafts together when the housings are in aligned position, a coil spring connected to the lower housing and having its opposite end connected to the housing securing means, a drum carried by the main driving shaft, and a cable passing around said drum and having its ends secured to a hand operated means, whereby the cable may be tightened around the drum for retarding the movement of the main drive shaft.
- 50 11. In a wind propelled outboard motor, comprising upper and lower aligned tubular housings hinged together, means for securing the upper housing to a boat, a main driving shaft in the upper housing, wind propelled means for driving the main shaft, a propeller shaft in the lower housing, a propeller carried by the lower housing and driven by a gearing from the propeller shaft, clutch means carried by the main shaft and the propeller shaft connecting the shafts together when the housings are in aligned position, a coil spring connected to the lower housing and having its opposite end connected to the housing securing means, a drum carried by the main driving shaft, and a cable passing around said drum and having its ends secured to a hand operated means, whereby the cable may be tightened around the drum for retarding the movement of the main drive shaft.
- 55 12. In a wind propelled outboard motor, comprising upper and lower aligned tubular housings hinged together, means for securing the upper housing to a boat, a main driving shaft in the upper housing, wind propelled means for driving the main shaft, a propeller shaft in the lower housing, a propeller carried by the lower housing and driven by a gearing from the propeller shaft, clutch means carried by the main shaft and the propeller shaft connecting the shafts together when the housings are in aligned position, a coil spring connected to the lower housing and having its opposite end connected to the housing securing means, a drum carried by the main driving shaft, and a cable passing around said drum and having its ends secured to a hand operated means, whereby the cable may be tightened around the drum for retarding the movement of the main drive shaft.
- 60 13. In a wind propelled outboard motor, comprising upper and lower aligned tubular housings hinged together, means for securing the upper housing to a boat, a main driving shaft in the upper housing, wind propelled means for driving the main shaft, a propeller shaft in the lower housing, a propeller carried by the lower housing and driven by a gearing from the propeller shaft, clutch means carried by the main shaft and the propeller shaft connecting the shafts together when the housings are in aligned position, a coil spring connected to the lower housing and having its opposite end connected to the housing securing means, a drum carried by the main driving shaft, and a cable passing around said drum and having its ends secured to a hand operated means, whereby the cable may be tightened around the drum for retarding the movement of the main drive shaft.
- 65 14. In a wind propelled outboard motor, comprising upper and lower aligned tubular housings hinged together, means for securing the upper housing to a boat, a main driving shaft in the upper housing, wind propelled means for driving the main shaft, a propeller shaft in the lower housing, a propeller carried by the lower housing and driven by a gearing from the propeller shaft, clutch means carried by the main shaft and the propeller shaft connecting the shafts together when the housings are in aligned position, a coil spring connected to the lower housing and having its opposite end connected to the housing securing means, a drum carried by the main driving shaft, and a cable passing around said drum and having its ends secured to a hand operated means, whereby the cable may be tightened around the drum for retarding the movement of the main drive shaft.
- 70 15. In a wind propelled outboard motor, comprising upper and lower aligned tubular housings hinged together, means for securing the upper housing to a boat, a main driving shaft in the upper housing, wind propelled means for driving the main shaft, a propeller shaft in the lower housing, a propeller carried by the lower housing and driven by a gearing from the propeller shaft, clutch means carried by the main shaft and the propeller shaft connecting the shafts together when the housings are in aligned position, a coil spring connected to the lower housing and having its opposite end connected to the housing securing means, a drum carried by the main driving shaft, and a cable passing around said drum and having its ends secured to a hand operated means, whereby the cable may be tightened around the drum for retarding the movement of the main drive shaft.
